(57) **CLAIM**

The ornamental design for a gift box, as shown and described.

DESCRIPTION

FIG. 1 is a perspective view of a gift box showing my new design. The broken-lines of FIG. 1 are environmental only, and form no part of the claimed design.

FIG. 2 is a top plan view thereof;

FIG. 3 is a bottom view thereof;

FIG. 4 is a front elevational view thereof;

FIG. 5 is a rear elevational view thereof; and,

FIG. 6 is a left side elevational view, the right side being a mirror image of left side.
